UNITED STATES PATENT OFFICE

2,305,380

ELECTRIC PROTECTIVE SYSTEM

Martin A. Edwards, Scotia, N. Y., assignor to
 General Electric Company, a corporation of
 New York

Application May 31, 1940, Serial No. 337,982

4 Claims. (Cl. 175—363)

My invention relates to protective systems and more particularly to protective systems for electric valve translating apparatus.

In many applications it is important, in order to meet the load requirements, to operate a pair of electric valve means in parallel relationship. For example, the electric valve translating apparatus may comprise a pair of electric valve means connected to operate in parallel by means of a current-dividing reactor or reactance. In accordance with my invention described herein-after, I provide a new and improved protective system for arrangements of this nature.

It is an object of my invention to provide a new and improved protective system.

It is another object of my invention to provide a new and improved protective or control system for electric valve translating apparatus.

It is a further object of my invention to provide a new and improved protective system for electric valve apparatus which includes a pair of electric valve means connected to operate in parallel relationship by means of a current-dividing reactor and wherein means are provided to operate in response to the magnetization of the current-dividing reactor to provide an indication or initiate a circuit controlling or protective operation, when one of the electric valve means fails to conduct current, or conducts current at any time other than during predetermined intervals.

Briefly stated, in the illustrated embodiment of my invention I provide a new and improved control or protective system for electric valve translating apparatus wherein a pair of electric valve means are connected to operate in parallel relationship, that is, to conduct equal amounts of current concurrently during predetermined intervals of time. The division of current between the electric valve means is obtained by means of a current-dividing reactor or reactance to equalize the anode-cathode voltages thereof. I provide means responsive to the magnetization of the core member of the reactor to afford an indication or to initiate a circuit controlling operation when one of the electric valves fails to conduct current during the predetermined intervals, or when one of the electric valve means conducts current at any time other than during the predetermined intervals, or when one of the electric valves is late in starting to conduct current.

For a better understanding of my invention, reference may be had to the following description, taken in connection with the accompanying

drawing, and its scope will be pointed out in the appended claims. Fig. 1 of the drawing diagrammatically illustrates an embodiment of my invention as applied to a polyphase rectifier, and Fig. 2 represents a detailed arrangement of the relay apparatus responsive to the magnetization of the current-dividing reactor. Fig. 3 diagrammatically illustrates a modification of my invention which employs a separate or auxiliary control relay.

Referring now to Fig. 1 of the drawing, I have there diagrammatically illustrated my invention as applied to an electric valve converting system, such as a rectifier, for energizing a direct current load circuit 1 from an alternating current supply circuit 2 through electric translating apparatus comprising a transformer having primary windings 3 and groups of secondary windings 4 and 5. The groups of secondary windings 4 and 5 may be interconnected through an interphase transformer 6 so that the system operates as a double three-phase system. The translating apparatus also includes a plurality of electric valve means 7—18, inclusive, of the type comprising an ionizable medium, such as a gas or a vapor, and each having an anode 19, a cathode 20, and may have an associated control member of the immersion ignitor type. The control circuits which, of course, are employed to render the electric valve means 7—18 conducting are not shown. It will be understood, however, that suitable control circuits for transmitting unidirectional impulses of current to the control members 21 may be used to render the electric valve means conductive in a predetermined order or sequence so that the pairs of electric valves conduct current in parallel relationship. Inasmuch as mercury pool cathodes are employed, it is to be understood that in this particular arrangement the ionizing medium is mercury vapor. Suitable circuit controlling means, such as circuit breakers 22, may be connected in series relationship with the anode-cathode circuits of the respective groups or pairs of electric valves.

45 I provide a plurality of current-dividing reactances or reactors 23—28, inclusive, each of which is associated with a different one of the pairs of electric valve means, and each of which comprises a core member and an associated winding 29 having terminal connections 30 and 31 and an electrically intermediate connection 32, which is connected to the associated winding of the power transformer through the associated circuit breaker 22. The windings 29, by virtue 50 of the intermediate connection 32, provide differ-

ential current conducting sections each associated with a different one of the electric valve means.

I provide a plurality of relay means 33, each supported by the core member of the associated current-dividing reactor and which is responsive to the magnetization of the core member. The relays 33 may be arranged to be responsive to the magnetization of the core member occasioned by failure to conduct of one of the associated electric valve means, or responsive to the magnetization of the core member caused one of the electric valve means conducting current at a time other than during the predetermined intervals. In addition, the relays 33 are responsive to the magnetization of the core members occasioned by irregular starting of the associated valves as, for example, when one of the electric valves of a pair is initiated in its operation at a time subsequent to the operation of the other.

There is also provided a circuit, such as an indicating circuit 34, which affords a visual indication upon loss of control or failure to conduct of one valve in the respective groups of electric valves. The indicating circuit 34 includes a circuit 35 which is connected to the contacts of relays 33 and includes a suitable visual indicating device, such as a glow discharge valve 36 having a minimum potential ionizing characteristic. The glow discharge valve 36 may be connected to a portion of a voltage divider 37 and may be energized from a suitable source of current, such as a source of alternating current 38, supplied by secondary winding 42 of transformer 39. When the contacts of relays 33 are closed, a voltage is applied to the terminals of the glow discharge valve 36, effecting ionization thereof and affording a visual indication.

A suitable relay means 43 is also associated with the indicating circuit 34. The relay means 43 may be provided with an actuating coil 44 and contacts 45 which are normally maintained in the closed circuit position, the actuating coil 44 being normally energized from circuit 38. However, when the contacts of relays 33 close, the actuating coil 44 is shunted thereby permitting the relay to open its contacts 45.

I provide a second control circuit 46 to afford an indication, or to initiate a control or protective operation, if one of the electric valves loses control or fails to conduct current for a predetermined interval of time. A second relay 47 is provided to open circuit 46 if the fault condition exists for a predetermined number of cycles of voltage of circuit 2. Relay 47 includes an actuating coil 48 which may be energized from a suitable source of current, such as a direct current circuit 49, through current limiting resistance 50. A source of direct current may be provided by a rectifier 51 energized from secondary windings 41 of transformer 39. The relay 47 is arranged so that its contacts 52 are normally closed and is arranged to open its contacts 52 with a definite time delay if the fault exists for a predetermined interval of time.

Fig. 2 diagrammatically illustrates a modification of one of the current-dividing reactors, such as current-dividing reactor 23, and the associated relay 33. The current-dividing reactor 23 comprises a core member 53 and the winding 29 is wound around the middle leg of the reactor. The relay 33 comprises a pair of contacts 54 and 55 which are supported by the core 53 by means of suitable members such as non-magnetic brackets 56 and 57. The movable contact 55

may be mounted on and actuated by a magnetic armature 58 which is attracted to the core member 53 when the core becomes magnetized.

The relay arrangement shown in Fig. 2 is responsive to the magnetization of the core member 53 occasioned by irregular operation or faulty operation of one of the electric valves in the associated group. That is, the relay 33 will close its contacts 54 and 55 in response to loss of control or failure to conduct of one of the associated electric valves, thereby closing its contacts 54 and 55 and initiating the operation of circuit 34 or 46.

The operation of the embodiment of my invention shown in Fig. 1 will be explained by considering the system when it is operating as a polyphase rectifier to energize the direct current load circuit 1. It will be understood that by virtue of the interphase transformer 6, the rectifying system operates as a double three-phase system and that each pair of electric valves conducts current for substantially 120 electrical degrees, but for only 60 electrical degrees with any one other pair of electric valves. Due to the current-dividing reactors 23-28, the respective pairs of electric valves conduct current in parallel relationship.

The electric valves are rendered conductive in a predetermined order or sequence by excitation circuits (not shown). These excitation circuits supply unidirectional impulses of current to the respective control members 21 to effect the desired sequential operation. Furthermore, the control members in each group of electric valves or each pair of electric valves are energized simultaneously so that the electric valves conduct current in parallel relationship.

In the event one of the electric valves in any one of the groups departs from its normal mode of operation, that is, fails to conduct current or loses control by conducting current at any time other than during the predetermined intervals, circuit 34 will substantially coincidentally effect a visual indication of this irregular operation due to the luminescence of the glow discharge valve 36, and if the fault condition exists for a predetermined number of cycles of the voltage of circuit 2, circuit 46 will be controlled to afford an indication of the continued irregular operation. Circuit 46 may be used to initiate a circuit controlling or protective operation in response to the continued loss of control or failure to conduct.

Referring more particularly to the operation of circuit 34 in the event one of the electric valves in a particular group loses control or fails to conduct during the desired intervals, the contacts 54 and 55 of the associated relay will be closed, shunting the actuating coil 44 of relay 43. Concurrently with this operation, closure of the contacts 54 and 55 completes the circuit for the energization of the glow discharge valve 36, affording an immediate visual indication of irregular operation. When the contacts 45 of relay 43 open, the actuating coil 48 of relay 47 is energized and the contacts 52 of relay 47 are opened with a time delay. If the fault exists for the pre-established interval of time, contacts 52 are opened.

It is to be understood that if one of the electric valves fails to conduct current during predetermined intervals or loses control by conducting current at any time other than during the intervals, or if the pairs of valves do not become conductive at precisely the same instant, there

will be established in the core members 53 of the current-dividing reactors 23-28 magnetic fluxes due to the differential effect of windings 29. Consequently, the relays 33 will be actuated and the contacts 54 thereof will be closed to initiate the above-described sequence of operation.

In Fig. 3 a modification of my invention is shown which is similar generally to the arrangement of Fig. 1 and corresponding elements have been assigned like reference numerals. A separate or auxiliary relay 59 is employed which is similar in many respects to the relay structure shown in Fig. 2. The relay 59 comprises a core member 60 having a pair of opposing winding sections or windings 61 and 62 and having contacts 63 and 64 which are mounted on an armature member 65 which, in turn, is responsive to the magnetization of the core member 60. Winding 61 is connected in series relation with electric valve 7, and winding 62 is connected in series relation with electric valve 8.

If the electric valves conduct current in parallel relationship, that is, conduct during the same intervals of time and initiate the periods of conduction at the same instant, there will be no magnetization of the core member 60 and hence the armature 65 will not be actuated. However, if the electric valves 7 and 8 fail to conduct current during the same intervals of time, or lose control by conducting current during intervals other than the predetermined intervals of time, or fail to initiate the intervals of conduction at the same instant, the armature 65 will be actuated due to the magnetization of the core 60, closing contacts 63 and 64 and thereby controlling circuit 35.

While I have shown and described my invention as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, an alternating current circuit, a direct current circuit, electric translating apparatus connected between said circuits and comprising a pair of electric valves, means for dividing the current between said electric valves so that said electric valves conduct current in parallel relationship and comprising a magnetic core member having a winding associated therewith having differentially opposed sections thereof each associated with a different one of said electric valves, a control circuit, means responsive to a magnetic condition of said core member to control the energization of said control

5 circuit when one of said electric valves fails to conduct current, a second control circuit, and means for controlling the energization of said second control circuit when said one electric valve fails to conduct current for a predetermined number of cycles of said alternating current circuit.

2. In combination, an alternating current circuit, a direct current circuit, electric translating apparatus connected between said circuits and comprising a pair of electric valves, means for dividing the current between said electric valves so that electric valves conduct current in parallel relationship and comprising a magnetic core member having a winding associated therewith having differentially opposed sections thereof each associated with a different one of said electric valves, a control circuit, means responsive to the magnetization of said core member to energize said control circuit when one of said electric valves fails to conduct current, a second control circuit, and means for energizing said second control circuit when said one electric valve fails to conduct current for a predetermined number of cycles of said alternating current circuit.

3. In combination, an alternating current circuit, a direct current circuit, electric translating apparatus connected between said circuits and comprising a pair of electric valve means arranged to conduct current in parallel relationship, a control circuit, and means for controlling said control circuit in response to the current conducted by the electric valve means comprising an inductive device having a core member, a winding associated with said core member having a pair of differential sections each responsive to the current conducted by a different one of said electric valve means and armature means mounted on said core member and comprising a magnetic portion directly responsive to the magnetization of said core member.

4. In combination, an alternating current circuit, a direct current circuit, electric translating apparatus connected between said circuits and comprising a pair of electric valve means and an inductive device for controlling said electric valve means so that said electric valve means conducts current in parallel relationship, a control circuit, and means for controlling said control circuit in response to the current conducted by said electric valve means comprising a magnetic relay having a core member, a winding associated with said core member having a pair of differential sections each responsive to the current conducted by a different one of said electric valve means, a pair of contacts and armature means mounted on said core member and comprising a magnetic portion directly responsive to the magnetization of said core member for actuating said contacts.

MARTIN A. EDWARDS.
